UNITED STATES PATENT OFFICE.

WILLIAM MONROE WHITE, OF MILWAUKEE, WISCONSIN.

HYDRAULIC NOZZLE.

1,155,631.

Specification of Letters Patent.

Patented Oct. 5, 1915.

Application filed September 29, 1913. Serial No. 792,879.

To all whom it may concern:

Be it known that I, WILLIAM MONROE WHITE, a citizen of the United States, residing at Milwaukee, in the county of Milwaukee and State of Wisconsin, have invented a certain new and useful Improvement in Hydraulic Nozzles, of which the following is a specification.

This invention relates to improvements in the construction of hydraulic nozzles such as are used in hydraulic power plants, hydraulic mining, and similar arts.

An object of the invention is to provide a hydraulic nozzle which is simple in construction, efficient in operation and in which a means for changing the direction and size of the jet discharged from the nozzle is confined entirely within a stationary nozzle casing.

20 One of the more specific objects of the invention is to provide simple and easily accessible means for permitting ready manipulation of the jet discharged from the nozzle.

25 Another object is to provide a nozzle in which an adjustable jet size changing means is carried by a movable jet direction changing means, these means being normally lock-gearied to each other so that the jet direction changing means may be manipulated without affecting the size of the jet, while the jet size changing means may be readily manipulated irrespective of the direction of the jet.

30 The present invention is an improvement in the devices disclosed in patent 1,055,958, granted March 11, 1913, and those disclosed in application S. N. 754,124, filed March 12, 1913.

40 A clear conception of an embodiment of the invention may be had by referring to the drawing accompanying and forming a part of this specification in which like reference characters designate the same parts in the various views.

Figure 1 is a central vertical section through a nozzle, turbine casing and foundation, showing the nozzle delivering a jet of water against the buckets of an impulse water wheel. Fig. 2 is an enlarged transverse horizontal section through the nozzle disclosed in Fig. 1, showing various details of construction of the nozzle.

45 The stationary nozzle casing, see Figs. 1 and 2, consists essentially of a rear casing

portion 9 formed integral with the water inlet pipe 24 for supplying water under pressure to the nozzle, and a front cover 7 secured to the rear casing portion 9. The cover 7 is also secured to the lower front 60 turbine casing 6 and seals the joint between the turbine casing and the nozzle casing. The turbine casing comprises a lower casing 5 supported upon a suitable foundation 26 and secured to the lower front turbine 65 casing 6, and a cover casing 3 inclosing the upper portion of the casing 5. The runner 1 is mounted in suitable bearings in the casing 5 and is provided at its periphery with a series of impulse buckets 2 adapted 70 to receive the jet 25 normally delivered from the nozzle. The deflector 4 is secured to the casing 5 and serves to divert that portion of the jet which does not have its velocity entirely abstracted by the buckets 75 2 of the impulse wheel.

The jet direction changing means comprises a deflecting hood 10 through which the nozzle orifice is formed, and a suitable hood supporting ring 12 formed with stub 80 shafts 27, 33, projecting laterally therefrom. The stub shafts 27, 33, are rotatably mounted in trunnions or bearings 30, 31, formed in the stationary casing and form pivots about which the hood 10 may be 85 swung. The points of emergence of the shafts 27, 33, from within the stationary nozzle casing, are provided with suitable stuffing boxes 29, 32, which serve to prevent leakage of water to the atmosphere along 90 the stub shaft bearings. The outer free end of the stub shaft 27 is provided with a suitable crank 28, to which the means for swinging the hood 10, which means may be of any of the well known forms such as 95 disclosed in the patent above referred to, may be connected.

The needle support and guide 14 is secured centrally within the hood supporting ring 12 by means of radial ribs 13. This 100 guide 14 is bored in line with the nozzle orifice and supports the jet size changing means or needle 11. The needle 11 is formed with a rearwardly projecting screw-threaded portion 15 which coacts with the internal 105 screw threads of a sleeve 16. The sleeve 16 is fixed within the guide 14.

The needle operating shaft 20 is rotatable and reciprocable within a bearing formed in the rear cap 23. The shaft 20 penetrates 110

the nozzle casing, the point of emergence of the shaft from within the nozzle casing being packed by means of a suitable stuffing box 21. The outer end of the shaft 20 is provided with a suitable operating wheel 22 or similar device, by means of which the shaft 20 may be rotated, either manually or automatically.

The end of the operating shaft 20 which is within the nozzle casing is connected to the rear end of the portion 15 of the needle 11 by means of a universal or flexible connection consisting of a link 18 and a pair of connecting blocks 17, 19. The blocks 15 17, 19, are each provided with two bores formed at right angles to each other. Each of these bores receives a pin which is mounted in holes in the adjacent elements connected by the respective blocks 17, 19. The block 17 with its transverse pins connects the end portion 15 of the needle 11 with one end of the link 18, forming a universal joint between these elements. The block 19 with its transverse pins connects the inner end of the shaft 20 with the other end of the link 18 and forms a universal connection between these elements. These two universal joints and the link 18 constitute a flexible connection or shaft between the operating shaft 20 and the needle 11. It is not, however, necessary to constitute the flexible connection of a pair of universal joints with the connecting link as disclosed, as any other device accomplishing a similar purpose could be substituted without departing from the scope of the present invention.

The joint between the outer spherical surface of the hood 10 and the casing cover 7 is provided with a suitable cup leather packing 35 which is clamped between a packing retainer ring 36 and the front cover cap 8 by any suitable clamping means. The cap 8 is secured to the casing cover 7 by 45 means of studs or cap screws 34.

During the normal operation of the nozzle, water under pressure is supplied through the inlet pipe 24, and after passing through the nozzle casing and deflecting hood 10, is discharged through the hood orifice in the form of a jet 25 and normally against the buckets 2 of the impulse wheel.

If it is desired to deflect the jet 25 from the buckets 2, placing the jet in the position indicated in dot and dash lines in Fig. 1, this may be done by turning the hood 10 and the elements connected thereto about the axes of the stub shafts 27, 33, by means of the crank 28. If it is desired to vary the size of the jet discharged from the nozzle orifice, this may be done by rotating the needle 11 by means of the operating wheel 22. Rotation of the needle 11 will cause the screw-threaded portion 15 thereof to 65 move along the sleeve 16, thus changing the

position of the needle 11 relative to the nozzle orifice. The screw-thread coaction between the needle 11 and the sleeve 16 forms a lock-geared connection between these elements.

By employing a flexible connection between the operating shaft 20 and the needle 11, the position of the needle 11 relative to the hood 10 may be readily varied irrespective of the angular position of the hood 10. 75 By mounting the needle 11 in the screw-threaded sleeve 16 which is secured to the hood 10, the direction of the jet discharged from the hood 10 may be varied without affecting the size of the jet, since the needle 11 is locked to the hood during movement thereof. There is, however, nothing preventing simultaneous adjustment of the needle 11 and deflection of the hood 10 if such action is desired. 80

By permitting the fluid under pressure from within the nozzle to act on both sides of the deflecting hood 10, the forward pressure on the inner surface of the hood 10 is effectively balanced and rotation of the hood 90 is readily permitted. The use of a stationary nozzle with a deflecting hood therein furthermore permits effective sealing of the turbine casing.

It should be understood that it is not desired to be limited to the exact details of construction shown and described, for obvious modifications will occur to a person skilled in the art.

It is claimed and desired to secure by Letters Patent,—

1. In a nozzle, a casing, jet-size-changing means shiftable angularly and adjustable to change the size of the jet, and a flexible shaft normally intersecting the axis 105 of angular shift for adjusting said jet-size-changing means.

2. In a nozzle, a casing, jet-direction-changing means within said casing, adjustable jet-size-changing means carried by said jet-direction-changing means, and a flexible shaft within said casing for operating said jet-size-changing means.

3. In a nozzle, a casing, jet-direction-changing means within said casing, means for operating said jet-direction-changing means, adjustable jet-size-changing means carried by said jet-direction-changing means, and a flexible shaft directly connected to and operating said jet-size-changing means.

4. In a nozzle, a casing, jet-direction-changing means within said casing, jet-size-changing means carried by said jet-direction-changing means, said jet-size-changing means being adjustably normally lock-geared to said jet-direction-changing means, and said parts being locked during movement of said jet-direction-changing means, and means extending from without said casing through and coacting directly with same 130

and connected directly with and for adjustment of said jet-size-changing means.

5. In a nozzle, a casing, a hood movable within said casing, a needle within said hood, said needle being adjustably normally lock-geared to said hood and said parts being locked during movement of said hood, and means extending from without said casing through and coacting directly with 10 same and connected directly with and for adjustment of said needle.

6. In a nozzle, a casing, a hood movable within said casing and having a screw-threaded sleeve fixed thereto, a needle having a screw-threaded portion coacting with 15 the screw threads of said sleeve, and flexible

means for rotating said needle within said hood.

7. In a nozzle, a casing, a hood movable within said casing, a needle carried by and 20 rotatable for adjustment within said hood, a shaft extending from without said casing through and coacting with said casing, and a flexible connection between said shaft and said needle.

25 In testimony whereof, the signature of the inventor is affixed hereto in the presence of two witnesses.

WILLIAM MONROE WHITE.
